FIG. 1

FIG. 2

FIG. 3

FIG. 4

FIGURE 1 is a plan view of a bracelet or similar article, showing my new design, portions thereof being shown broken away to indicate indeterminate length;

FIGURE 2 is a side elevational view thereof;

FIGURE 3 is a bottom plan view thereof; and

FIGURE 4 is an enlarged fragmentary perspective view thereof.

The essential features of the design reside in the full line portions of the drawings.

I claim:

The ornamental design for a bracelet or similar article, as shown and described.
